UNITED STATES PATENT OFFICE.

CHARLES L. SETTERGREN, OF PHILADELPHIA, PENNSYLVANIA.

SLAB-HOLDER FOR RUBBING-BEDS.

1,116,333

Specification of Letters Patent.

Patented Nov. 3, 1914.

Application filed July 3, 1914. Serial No. 345,902.

To all whom it may concern:

Be it known that I, CHARLES L. SETTERGREN, a citizen of the United States, residing at Philadelphia, in the county of Philadelphia and State of Pennsylvania, have invented new and useful Improvements in Slab-Holders for Rubbing-Beds, of which the following is a specification.

This invention relates to an improved device for holding marble slabs while finishing the edges of the same upon the usual rubbing bed. The present device permits the slabs to be set at the desired angle upon a neighboring table, secured in position in the device, and then swung thereby over and into contact with the revolving surface of the rubbing bed. Aside from these objects many additional advantages arise from its use and operation and these are fully brought out in the following specification with reference to the accompanying drawings, in which:

Figure 1 is a plan view of the preferred form of the device; Fig. 2 is an elevation of the same; Fig. 3 is a front elevation of the gang frame and clamps; Fig. 4 is an end view of the same; Fig. 5 is a section on the line 5—5 of Fig. 3; Fig. 6 is an enlarged detail of the scale and its support; and Fig. 7 is an enlarged detail view partly in section of the cushioned block for clamping a slab.

Referring to the drawings, the invention primarily comprises the upright beam 10, pivoted in an overhead joist 11 and floor or suitable base 12 to swing in a horizontal plane upon the operation of the lever 13 which can be secured in either extreme position by engagement with the respective bifurcated brackets 14. The beam 10 carries at right angles and adjacent to its upper end a crane beam 15 braced by a member 16, said crane in turn being provided with a diverging band 17 secured as shown to said beam 15 and pivotally supporting at its opposite lower ends a board or crane 18, operative to be set and held in any angular position with respect to said crane by expansion rods 19 pivotally secured to said crane and board 20 and 21, respectively. The device is adapted to swing, as shown in Fig. 1, either over or away from the revolving disk or table 25 pivoted at 26 and carrying upon its surface the usual abrasive material.

The board 18 is recessed as at 27 and

carries any desired number of supporting mechanisms for slabs 28. Said mechanisms comprise plates 30 angularly adjustable on the board by bolts, actuated by hand wheels 31, while passing through and in slidable engagement with said plates are supporting rods 32 carrying upon their upper ends a head 33 provided with a bracket arm 34, in turn carrying a scale 35. The rods 32 carry upon their lower ends inverted V-shaped members 38 vertically slidable against the face of the board and substantially in alignment with the recess 27, though said rods and members can be set angularly within certain degrees by adjusting the plates 30. The members 38 are held against said board by brackets 39 and 40, which are horizontally adjustable as the bolts 41 shift in the slots 42 prior to setting and securing the former. The members 38 terminate at their lower ends in elongated plates 43, through which are adjustably secured screws 46 with hand wheels 47 and revolvably secured by a screw 48 in the socket 49 of a clamp head 50 secured in the forward face of which as by dove-tailing is a cushion 51 of relatively soft material such as lead, and various alloys.

To assist in securing a slab to one of the members 38 a rod 55 having a head 56 engaging the rear vertical edge of said slab is passed through one side or leg of said member and secured by a bolt 57. Adjacent to the top of the board 18 are secured braces 58 through which are adjustably mounted rods 59 having heads 60 and actuated by hand wheels 61, said heads being adjustably positioned by the actuation of said wheels to any desired distance below the arm 34 as indicated by the scale 35.

During the operation of the device, when the lower edge of a slab is rubbed down to the desired extent, the arm 34 contacting with the head 60 prevents said slab from dropping further. By this device it is obvious that several slabs may be "rubbed" simultaneously and a bevel set for those edges by adjusting the plates 30 and predetermined by the rod 59 the final width of the respective slabs.

I claim:

1. A support for slabs, comprising a frame, a vertically movable member, transversely adjustable guides for said member, a series of clamps on said member, and

means to predetermine the movement of said member in one direction and an angularly adjustable guide for said member.

2. The combination of a revolving rubber bed, with a revolving crane, angularly adjustable means to secure a slab to said crane at varying elevations, and means to move said crane over said bed.

3. The combination of a revolving bed, 10 with an oscillatory crane, a frame supported by said crane, and angularly adjustable means on said frame to support a plurality of slabs in angular adjustment.

4. The combination of a revolving rubber bed, with an oscillatory crane, a vertically movable frame supported in angular adjustment by said crane, angularly adjustable means on said frame to support a plurality of slabs, and means to predetermine the extent of movement of said frame. 15 29

In testimony whereof I affix my signature in presence of two witnesses.

CHARLES L. SETTERGREN.
